US00D665548S

(12) **United States Design Patent**
Arvinte et al.

(10) **Patent No.:** **US D665,548 S**
(b4) **Date of Patent:** **** Aug. 14, 2012**

(54) **PAINT BRUSH CLEANER**

(75) Inventors: **Roméo Arvinte**, Laval-des-Rapides (CA); **François Panfili**, Berthierville (CA)

(73) Assignee: **A. Richard Tools Co.**, Berthierville, Quebec (CA)

(**) Term: **14 Years**

(21) Appl. No.: **29/376,031**

(22) Filed: **Sep. 30, 2010**

(30) **Foreign Application Priority Data**

Mar. 31, 2010 (CA) 134992

(51) **LOC (9) Cl.** **08-99**

(52) **U.S. Cl.** **D32/35**
